UNITED STATES PATENT OFFICE

143,613

DESIGN FOR AN ASH TRAY

Willard F. Meyers, Toledo, Ohio, assignor to Owens-Illinois Glass Company, Toledo, Ohio, a corporation of Ohio

Application September 26, 1945, Serial No. 122,358

Term of patent 7 years

(Cl. D85—2)

To all whom it may concern:

Be it known that I, Willard F. Meyers, a citizen of the United States, residing at Toledo, in the county of Lucas and State of Ohio, have invented a new, original, and ornamental Design for an Ash Tray, of which the following is a specification, reference being had to the accompanying drawing forming a part thereof.

In the drawing:

Fig. 1 is a plan view of an ash tray showing
my new design.

Fig. 2 is a side elevational view thereof with parts in section.

I claim:

The ornamental design for an ash tray, substantially as shown.
